THERAPEUTIC PRODUCT AND PROCESS

Hans Christian Hagedorn, Gentofte, Birger Norman Jensen, Copenhagen, and Ingrid Wodstrup-Nielsen, Gentofte, Denmark, assignors to Nordisk Insulinlaboratorium, Gentofte, Denmark, a corporation of Denmark

No Drawing. Application February 14, 1936,
Serial No. 63,890. In Denmark April 8, 1935

8 Claims. (Cl. 167—75)

It is the object of our invention to control the rate at which 'Insulin' becomes effective in the body, and to obtain a more effective utilization of 'Insulin.'

5 More specifically, the object is to make an effective 'Insulin' product the solubility of which in the fluids of the body tissues is limited to a very low but controlled value, so that the 'Insulin' will become effective at a slow but pre-
10 determined rate over an extended period of time; and thus to make the effect on administering such product to a patient not only more lasting but also more uniform between successive doses as compared with ordinary 'Insulin', and so to
15 lessen the danger of having an 'Insulin' effect that is either inadequate or excessive at any time and thus to hold the blood sugar at all times more nearly like that of a normal person and incidentally to lessen thereby the total quantity
20 of 'Insulin' necessary per day for the effective control of diabetes.

It is well known that the effect of the usual administration of ordinary 'Insulin', (which is most commonly in the form of the hydrochloride) by subcutaneous or intramuscular injection from one to five times per day, is far from uniform between doses; for after each injection there tends to be for a time too great an 'Insulin' effect in the blood stream and a corresponding tendency to hypoglycemia, while after a few hours the 'Insulin' is dissipated and there is available too little 'Insulin' effect and a consequent tendency to the diabetic condition of hyperglycemia.

35 The situation is the more serious in the more severe cases of diabetes, where the patient's own sugar-control approaches zero. In such severe cases, and to a less extent in milder cases, this has made necessary the administration of 'Insulin' in small doses at inconveniently frequent intervals; for there is danger to the patient both from too large a dose and from too long a period between successive doses.

40 Many attempts have been made to counteract this situation, but with little success. Among the things which have been tried are the injection of 'Insulin' in the form of a suspension in oil; the application of 'Insulin', in various forms, by inunction for absorption through the skin; the slowing down of the absorption of 'Insulin' by the use of epinephrine; and the injection of 'Insulin' in the form of an emulsion with various lipoids, with or without some emulsion-stabilizer
45 co-present. These are all open to serious objec-

tion from the standpoint of use in the human diabetic.

In addition, various compositions of 'Insulin', whether or not there was a chemical or physical combination or a mere mixing of the ingredients, have been tried, but with very little success in meeting this situation prior to our present invention.

Our invention may also be considered to approach the problem by the use (at least in part) of what may be compounds of 'Insulin'—but of a new type. According to that invention, we form a product (possibly at least in part a chemical compound) by mixing 'Insulin' and a protamine; and that product includes what may be called an 'Insulin'-protamine composition, which at about the hydrogen ion concentration of the fluids of the body tissues is almost insoluble in such fluids, so that when such product is injected the 'Insulin' is taken up by such fluids from the site of injection only very slowly and over a relatively long period of time. In this way, the peaks of 'Insulin'-effect are lowered and the valleys of 'Insulin'-effect are raised; both the danger of hypoglycemia and the danger of hyperglycemia are greatly lessened; and the amount administered at a dose may with safety be increased and the time between successive injections may with safety be lengthened. By proper selection of the protamine, and of its concentration, the rate of absorption of the 'Insulin' into the fluids of the body tissues may be controlled with considerable effectiveness.

We have found that protamines somehow combine with 'Insulin' to form products, possibly chemical or physical compounds of some nature, which when at or near the hydrogen ion concentration of the fluids of the body tissues are definitely less soluble in those fluids than is ordinary 'Insulin'. Such a product, which we call an 'Insulin'-protamine composition, may safely be injected either subcutaneously or intramuscularly, (desirably not intravenously if the slow effect is desired, for on intravenous injection the effect of our product is substantially the same as that of ordinary 'Insulin') and if at or near the hydrogen ion concentration of the fluids of the body tissues is not immediately entirely taken up from the site of injection by such fluids; but instead, in slowly decreasing amount, remains at the site of injection for a considerable number of hours, during which the 'Insulin' is slowly taken up by the fluids of the body tissues and utilized for a fairly uniform sugar control over a fairly long period.

Protamines, which are relatively simple alkaline proteins ordinarily obtained from the sperm of fish, have been known for a great many years—at least one as early as 1868, when Miescher produced salmine. They have been known as protein precipitants since about 1890, when that property was first observed by Kossel, who with his co-workers produced a number of protamines and determined the general nature of their chemical constitution.

By the term "protamine", we mean those very simple basic proteins and protein split-products, commonly obtainable from the sperm and/or testicles of fishes, which in their composition include arginine and may include either or both histidine and lysine.

Among the protamines which have been combined with "Insulin", to produce "Insulin"-protamine compositions that give the desired results in varying degree, are the following:

Clupeine	(from herring sperm)
Salmine	(from salmon sperm)
Scombrine	(from mackerel sperm)
Cyclopterne	(from lump-sucker sperm)
Sturine	(from sturgeon sperm)
Salmiridine	(from the sperm of <i>Salmo trideus</i> Gibbons, or rainbow trout)

Protamines derived from the sperm of the following species of fish:

Scientific name	Common name
<i>Salmo fontinalis</i> Mitchill	Brook trout.
<i>Salmo trutta</i> Linné, Forma Fario	River trout.
<i>Coregonus lavaretus</i> Linné	European white fish.
<i>Belone acus</i> Rissö	Needle fish.
<i>Alosa alosa</i> Cuvier	Allie shad.
<i>Cottus scorpius</i> Linné	Sculpin.

Excellent results have been obtained with salmiridine. This protamine, which so far as we know has not previously been described, is prepared from the testicles or the sperm of the *Salmo trideus* Gibbons or rainbow trout in the same general way that other protamines are prepared from the testicles or the sperm of other fishes.

The "Insulin"-protamine composition which is made from this particular protamine, and which may properly be called "Insulin"-salmiridine composition, has a very low solubility in the fluids of the body tissues. "Insulin"-clupeine composition, "Insulin"-scombrine composition, and "Insulin"-salmine composition, made by combining (perhaps chemically combining) "Insulin" with clupeine, scombrine, and salmine respectively, also have low solubilities in such fluids.

"Insulin"-protamine compositions have been used on diabetics of all ages and classes and with varying degrees of diabetic gravity. Most of the cases have been severe ones, some with various complications. Up to the present time, more than 15,000 blood-sugar determinations and more than 3,000 determinations of sugar and ammonia in the urine have been made in the course of our investigation of "Insulin"-protamine compositions.

The same patients have at times been treated alternately with ordinary "Insulin" and with "Insulin"-protamine composition; so that the controls were on the same patients who received the "Insulin"-protamine composition.

Our investigations show the following: The sharp peak effect usually seen three or four hours after the injection of ordinary "Insulin" is largely

and often wholly avoided by the use of "Insulin"-protamine composition. The effect of "Insulin"-protamine composition is more prolonged than that of ordinary "Insulin"; so that necessity for "Insulin" administration during the night, as is essential in certain cases when ordinary "Insulin" is used, is eliminated even in those cases. Without changing the number of injections, therefore, we can by using an "Insulin"-protamine composition diminish the blood-sugar fluctuations, reduce or suppress the glycosuria and reduce the ammonia excretion, and at the same time reduce the risk of the occurrence of either hypoglycemia or hyperglycemia; and we can do this, with effective sugar control throughout the entire twenty-four hours, with a smaller total quantity of "Insulin" per day than when ordinary "Insulin" is used.

To date no ill effects from "Insulin"-protamine composition have been observed. The injections have been substantially painless, and neither untoward local reactions nor untoward protein reactions have been observed. The "Insulin" action is slower, and is not so high and lasts over a longer period, with "Insulin"-protamine composition than with "Insulin". For this reason, in certain acute diabetic conditions (such as coma) ordinary "Insulin" is to be preferred if used subcutaneously or intramuscularly, because it works more rapidly. If desired, "Insulin"-protamine composition and ordinary "Insulin" may both be administered to the same patient, as by administering the ordinary "Insulin" during the day and "Insulin"-protamine composition at night, or under some conditions by administering both at the same time, either in the same injection or at different locations. The dose of "Insulin"-protamine composition varies with the condition of the patient, and must depend on the discretion of the physician, but ordinarily is based on the amount of "Insulin" the "Insulin"-protamine composition contains.

We have found that ordinarily the subjective effect on the patient is better when "Insulin"-protamine composition is used in the treatment than when only ordinary "Insulin" is used; because by using "Insulin"-protamine composition, either solely or in part, the patient may be relieved completely of feelings of uneasiness from acidosis or high blood sugar without requiring injections more frequently than two or at most three per day.

Thus by the use of "Insulin"-protamine composition the blood sugar may be controlled effectively through the entire twenty-four hours; and the dangerous diabetic condition of excessive blood sugar between midnight and morning, encountered in most diabetic patients under treatment with ordinary "Insulin" and making it necessary in many of those cases to administer "Insulin" during the night, may be completely eliminated.

The preparation of "Insulin"-protamine composition is very simple. Ordinary "Insulin" (usually in the form of "Insulin" hydrochloride) and the protamine to be used are simply brought together at a suitable hydrogen ion concentration so that they have an opportunity to interact on each other to produce the desired "Insulin"-protamine composition. Neither the "Insulin" nor the protamine is necessarily pure, as either or both may be commercial or technical products; but purity is desirable, as it promotes stability. We do not with certainty know the nature of the interaction between the two components; and it

may be that the resultant product involves some kind of physical or chemical combination.

The two components may be in almost any proportions. Indeed, the presence of an excess of either component is in certain instances desirable. Thus an excess of 'Insulin' in the composition gives both a prompt action and a continued action, which is desirable in some conditions; while an excess of protamine in the composition 10 serves as a protein-precipitant to precipitate proteins in those fluids of the body tissues which come into contact with the injected material, and thus to reduce the solvent-power of those fluids for the 'Insulin'-protamine composition.

15 Usually the two components are brought together in solution, conveniently but not necessarily in water solution, as interaction is thereby facilitated; and it is desirable that the solution as administered be buffered, with a non-toxic 20 buffer, to a hydrogen ion concentration which is approximately equal to that of the fluids of the body tissues, or between pH 6.7 and 8.0. The buffering need not be and desirably is not until just prior to administration. The buffering can 25 be obtained, for example, by appropriate concentration of the proper phosphates or borates, in known manner.

A highly satisfactory way of bringing about the reaction is to dissolve the two components in 30 separate quantities of water, the 'Insulin' in slightly acid water and the protamine in slightly alkaline water, and then to mix the two solutions, predetermining the hydrogen ion concentrations of the two component solutions so that when they 35 are mixed the final hydrogen ion concentration is in the neighborhood of that of the fluids of the body tissues.

The 'Insulin'-protamine composition which is thus formed is very nearly insoluble in water at 40 and near the hydrogen ion concentration of the fluids of the body tissues, so that the 'Insulin' is taken up by such fluids at a very slow rate when and after it is injected. Because of this high degree of insolubility, it is desirable that the material prepared as above outlined should be well 45 shaken immediately prior to injection, to be sure that all the 'Insulin'-protamine composition is in suspension and will be administered. We have noted no ill effects from the injection, in 50 spite of the fact that it is largely of a suspension.

The following examples show methods of making 'Insulin'-protamine composition:

Example A.—10 grams of ordinary 'Insulin' and 1 to 5 grams of salmiridine are dissolved in 55 liters of water—the 'Insulin' in 5 liters and the salmiridine in 1 liter—and the two watery solutions are simply mixed. The 'Insulin' solution is desirably adjusted to about pH 2.75; and the salmiridine solution is adjusted to about pH 8.0, 60 as by the addition of an appropriate phosphate buffer. When the two solutions are mixed this produces a hydrogen ion concentration of about pH 7.4. The resultant product, 'Insulin'-sal- 65 miridine composition, is a suspension, is administered as such, and its dosage is that amount which contains the quantity of 'Insulin' per se that it is desired to administer.

Example B.—10 grams of ordinary 'Insulin' and 1 to 5 grams of clupeine are dissolved in 6 70 liters of water—the 'Insulin' in 5 liters and the clupeine in 1 liter—and the two watery solutions are mixed. The hydrogen ion concentrations are suitably adjusted, as in Example A. The resultant product, 'Insulin'-clupeine composition, 75 is a suspension, is administered as such, and again

the dosage is that quantity which contains the amount of 'Insulin' per se that it is desired to administer.

In both of these examples, and others using different protamines (including those listed above) in the same general way, the concentrations of the solutions may be varied over a very wide range. Thus instead of dissolving the 10 grams of 'Insulin' in 5 liters of water, as suggested, that quantity of 'Insulin' may be dissolved in any desired quantity of water, depending upon the ultimate concentration desired. Similarly, the amount of water used to dissolve the protamine may be varied as desired.

We are not yet fully informed as to the stability 15 of 'Insulin'-protamine compositions over long periods of time. For that reason, as well as for other reasons, the components may be put in separate ampoules, the ordinary 'Insulin' in acid water in one ampoule, and the protamine in another ampoule in water suitably buffered so that the desired hydrogen ion concentration is obtained when the two solutions are appropriately mixed.

Another variant, and one which has been found 25 highly suitable, is to dissolve the 'Insulin' and the protamine together in acid water, say at about pH 2.75, and to put a suitable amount of this product in one ampoule; and in a companion 30 ampoule to put a buffer solution of such quantity and alkalinity that when it (or a proper amount of it) is mixed with the contents of the first ampoule a hydrogen ion concentration of about pH 6.7 to 8.0 is produced. The buffer solution may be a suitable phosphate solution. Before 35 administration, appropriate amounts of the contents of the two ampoules are suitably mixed, and the mixture injected into the patient.

A third way is to put a mixture of the 'Insulin' and the buffer in one ampoule, and to put a solution of the protamine in another ampoule, with the contents of both ampoules at about pH 7.4. The contents of the ampoules are appropriately 40 mixed just prior to administration, and the mixture (which is a suspension) is injected into the 45 patient.

Still another way is to have ampoules in sets of three, one ampoule with the ordinary 'Insulin', the second with the protamine, and the third with the buffer solution. These also will be appropriately 50 mixed prior to administration, and the mixture injected as before. This, however, involves more complexity than is usually desired or necessary.

Although we prefer that the protamine and 55 the 'Insulin' shall be kept separate until shortly before administration, yet it is entirely feasible, or at least certainly feasible if the material is not to be kept too long before use, to put the product up in single ampoules, containing the 60 'Insulin'-protamine composition in a buffered solution. Such buffered solutions of 'Insulin'-protamine composition have been kept for weeks without apparent loss of potency.

Either the protamine or the 'Insulin', or both 65 of them, may be in solid form at mixing, and the liquid necessary for injection may be provided in any other way, either during the mixing or at any time prior to administration.

Instead of using water as the solvent, for one 70 or more of the ingredients, we may use other solvents; such for instance as alcohol, ethylene glycol, propylene glycol, and glycerine, of varying concentrations, or indeed any non-toxic solvent in which the 'Insulin'-protamine composition is 75

substantially a suspension rather than a solution.

We claim as our invention:

1. The resultant product obtained by mixing 'Insulin' and a protamine.
- 5 2. The product obtained by bringing 'Insulin' and a protamine together, in a buffered solvent having a hydrogen ion concentration in the vicinity of that of the fluids of the body tissues.
3. An 'Insulin'-protamine composition.
- 10 4. An 'Insulin'-salmiridine composition.
5. An 'Insulin'-clupeine composition.
6. An 'Insulin'-salmine composition.
7. The process of making an 'Insulin' product

which at the hydrogen ion concentration of the fluids of the body tissues is absorbed relatively slowly into the blood stream, which consists in bringing 'Insulin' and a protamine together.

8. The process of controlling 'Insulin' action, 5 which consists in using with 'Insulin' a protamine which produces therewith a product materially more insoluble in the fluids of the body tissues than is 'Insulin'.
